UNITED STATES PATENT OFFICE.

HARRY T. DANIELS, OF PROVIDENCE, RHODE ISLAND.

LENS-EDGE-GRINDING MACHINE.

Application filed February 10, 1923. Serial No. 618,322.

This invention relates to an improved attachment for lens edge grinding machines, and has for its object to provide a frame or holder in which a lens is rotatably supported with its edge in proximity to a grinding wheel and to also provide means whereby the holder carrying the lens may be shifted to present the edge portion of the lens at different angles to the wheel without removing the lens from its mounted position therein. A further object of the invention is to provide means whereby the shifting of the lens-carrying means from one position to another cannot be effected without first lifting the support to move the lens clear of the grinding wheel.

The invention further consists in the provision of means whereby the lens with its supporting frame may be adjusted laterally with respect to the plane of rotation of the grinding wheel to compensate for the different angular positions of the lens relative to the wheel when its holder is set at its different working position.

A still further object of this invention is to so construct the mechanism that it may be readily attached to a standard type of grinding machine and use the regular patterns and lens holding face plate of that machine.

A still further object of the invention is to so mount the frame in the machine that the frame with the work may be lifted or swung back from operative position into a position to permit the ready removal of the finished lens and the positioning of a fresh lens in the holder.

With these and other objects in view, the invention consists of certain novel features of construction, as will be more fully described, and particularly pointed out in the appended claims.

In the accompanying drawing:

Figure 1 is a side elevation partly in section illustrating my improved mechanism also showing a portion of a grinding wheel in position to engage and grind the edge of a lens, the work-carrying head member being set on an angle to bevel the edge of the lens.

Figure 2 is a top view of the mechanism illustrated in Figure 1, showing portions broken away and partly in section to better illustrate the action of the machine, the work-carrying head member being set in an upright position.

Figure 3 is a detail showing an end view

of the pivot pin or shaft and its adjustable bearing mounted in each arm of the fork member.

Figure 4 is a detail in perspective showing 60 the V-shaped centering tool for determining the accurate setting of the lens through a backward or forward movement of its supporting cradle to bring its central plane in line with the axis of the pivoting pins in 65 the forked frame.

Figure 5 is a central sectional view through the head and cradle members showing the arrangement of the guiding pattern and the lens-supporting and driving mechanisms. 70

Figure 6 is a top view of a portion of the cradle partly in section with the head member mounted thereon and the pivoted lens clamp arm mounted on the head member which carries the lens clamping face plate. 75

Figure 7 is a modified construction showing a section at line 7—7 of Figure 1 with a cam mounted at the pivoting portion, for adjusting the lens-carrying mechanism laterally relatively to the plane of rotation of the 80 grinding wheel.

Figure 8 is a side elevation of this modified construction illustrated in Figure 7.

Figure 9 is an edge view of a hand clamp 85 with a lens mounted on the face plate, the clamp being employed for clamping the lens in position on the face plate to permit its accurate setting before being mounted in the machine.

Figure 10 is a face view of the device 90 shown in Figure 9.

Figure 11 shows a face view and sectional edge elevation of the face plate, respectively, to which the lens may be first clamped by the hand clamp. 95

Figure 12 is a face view of the lens pattern.

Figure 13 is a face view of one shape of lens showing the arrangement of dots placed upon its face to facilitate the proper setting 100 of the lens on its face plate before mounting both in the machine.

Fig. 14 is a detailed view of the means for locking the arm 55 in its clamping position.

By my improved device the lens may be 105 mounted in a holder pivotally mounted in a machine to be positioned to grind the edge of a lens at right angles to the face surface of the lens and swung to the desired angles on opposite sides of the center to 110 grind the edges of the lens in V-shape and all of which grinding positions may be ob-

tained without removing the lens from its holder; and the following is a detailed description of one construction of mechanism by which these advantageous results may be obtained:—

With reference to the drawings, 15 designates a portion of the main or standard machine on which my improved attachment is mounted, the same comprising essentially a bracket 16 having a base with suitable guides 17 in which the standard member 18 of my improved device is mounted and which standard may be slid on the bracket and adjusted laterally to accurately position the edge of the lens relatively to the working surface of the grinding wheel to compensate for the throw of the edge of the lens on the grinding wheel when its holder is moved to different angular positions.

In this standard, I have pivotally mounted a guide frame 19 by a pin 20, the latter passing through side ears 21 on the standard and also side ears 22 on the guide frame 19, as best illustrated in Figure 2. This pin is threaded at one end 23 and provided with a handle 24 at its opposite end by which the two pivoting ears may be clamped to bind the guide frame in any adjusted position. The guide frame is also provided with a stop lug 25 adapted to engage a boss 26 on the standard, to limit the upward throw of the lens-supporting mechanism hereinafter described.

In the front face of this guide frame is formed a dovetailed slot 26 in which is slidably mounted a correspondingly shaped member 27 formed on the forked frame 28 whereby this forked frame is adapted to be adjusted vertically in this frame through an operating handle 29, or by a micrometer screw adjustment presently described, and secured in any adjusted position by means of a binding screw 30.

Mounted between the arms 31 of the forked frame, is a cradle member 32 which is also provided with side arms 33, each arm being provided with a pivot pin 34 passing through the adjacent arm of the forked frame. The arms of this cradle 32 are adjustably mounted to be moved laterally, each on a bearing block 35 mounted on its pivot pin 34, the adjustment being obtained by a screw 36 threaded into its block, which screws are adapted to draw the cradle outwardly against the tension of the coiled spring 37 and permit it to move backwardly by action of said springs, by which construction it will be seen that the cradle is pivotally mounted upon the pins 34 whereby it is adapted to swing on these pivots to present the opposite edges of the lens at the desired angles to the working face of the grinding wheel 38 which wheel or stone is mounted on a shaft 39

and driven through a pulley 40 and is usually given a traverse motion by means, not shown.

In this cradle 32 is mounted a vertically reciprocating head member 41 on the dovetailed slide 42 and this head comprises a frame in the upper portion of which is mounted a cross shaft 43 having mounted on its outer end a pattern 44 which is of a size and shape to determine the size and shape to which the edge of the lens or work shall be ground. The edge of this pattern is arranged to engage the control or guide roll 45 mounted at the lower end of arm 46 which is hingedly connected through a pivot 47 at its upper end, to the cradle 32, and this arm is bound in operating position by means of a screw 48 whereby when it is desired to remove the pattern and replace it by one of another size and shape, it is only necessary to remove screw 48 to swing arm 46 outwardly whereby the replacing operation is readily effected.

The lens 49 to be ground is mounted between the inner and outer face plates 50 and 51 in this head, the outer face being adjusted to clamp the lens against the inner face plate by means of the adjustable screw 52 which is provided with a collar 53 engaging a bearing member 54 which is slidably mounted in the cross arm 55. This cross arm 55 is pivoted at one end at 56 with its free end arranged to be locked in closed position by means of a key 57, whereby when the elongated head of the key is rotated 90° it is adapted to register with a corresponding slot 58 in the end of the arm thus releasing the arm to be swung back with its lens clamps to permit the lens to be removed after having been finished.

In order to drive the lens clamps and the lens in time with its pattern 44, I have caused the pattern and the lens to be driven in unison through pinion 59, large gear 60 and pinion 61 by a motor 62 through a flexible shaft 63, worm 64 and worm gear 65, which latter is mounted on the short shaft 43, and in order to yieldably press the work against the grinding face of the wheel and cause it to be cut to the exact contour of the pattern, I have mounted a coiled spring 66 in an opening 67 in the cradle, the lower end of which spring is arranged to press against a pin 68 mounted in the head member which works in a slot 69 in the cradle whereby the pressure of the spring upon this pin acts through the frame of the head to press the edge of the pattern against the limit roll 45 and the edge of the lens against the grinding wheel while it with its pattern are being rotated.

It will be noted from the above that the head member carrying the work or lens, is mounted in the cradle member to move vertically to cause the head with its work to

follow the contour of the pattern. The cradle member is pivotally mounted on pivot pins 34 in the forked frame and is adapted to be laterally adjusted on its pivots whereby the central plane through the edge of the lens may be positioned on the axial line through the pivots; also by this construction the cradle with its work carrying head member may be set either vertically as illustrated in Figure 2, or at an angle on either side of the center (one of which is illustrated in Figure 1), for the purpose of grinding the desired V-shaped bevel on the edge of the lens.

Ordinarily in beveled work it is only required that the cradle member shall be in three positions, a vertical position and a predetermined angle on either side of the vertical and in order to lock the cradle in either of these desired positions, I have provided a disk member 70 with three notches 71 any one of which is adapted to be engaged by the free end of the latch bolt 72 to lock the cradle in any of its corresponding positions. This bolt is pressed into engaging position by the coiled spring 73 and it may be positively locked in engaging position by a fixed pin 74 supported on a bracket 77 and extending through a hole 75 in the enlarged end of the bolt.

In order to withdraw this bolt from locked position it is therefore necessary to raise the forked frame 31 in its guide frame 17 and so withdraw the pin from the bolt permitting the bolt to be then withdrawn against its spring pressure by means of the operating handle 76.

In order to determine the exact dimensions to which the minor axis of the lens shall be ground, I have provided a micrometer adjusting screw 80 which is carried in the forked frame 28, the lower end of the screw 78 providing a stop against the hardened bearing face plate 79 and which screw is adjusted to determine the limit of the downward movement of the lens. Means for compensating for the wear of the working face of the grinding wheel is provided for in the micrometer by adjustment of the central spindle 81 relatively to the sleeve 82 which adjustment is accomplished by first rotating back the head member 83 until the hole 84 registers with the binding screw 85 which is loosened permitting the central spindle 81 to be moved to adjust the micrometer reading to the desired point after which the set screw 85 is again set up.

In order to compensate for the different angular positions of the cradle so as to bring the edge of the lens into proper working relation with the face of the grinding wheel, in some cases I mount the standard member so that it may slide back and forth on its bracket and secure the same in adjusted position by a screw 86, while in other cases

a cam or eccentric member 87 may be mounted on a pivot pin 91 as illustrated in Figures 7 and 8 and I provide a handle member 88 on this pivot with a latch 89 adapted to engage any one of the three notches 90 in the collar 96 whereby when the cradle is swung to the position shown in Figure 1 the cam is thrown to the position opposite to that illustrated in Figures 7 and 8 and when the cradle is thrown to the opposite angular position the cam is drawn to the position illustrated in Figures 7 and 8.

In mounting the lens 49 in the machine, I first place a series of dots 92 as illustrated in Figure 13 along the major axis of the lens to be ground, I then place this lens upon a face plate 50 which is provided with peek holes 93 as best illustrated in Figure 11 through which holes the spots on the lenses may be observed and when the lens is in proper position as determined by aligning these spots with these peek holes the lens is bound by a hand clamp 94, see Figure 9, to the plate 50 and is subsequently positioned in the machine where it is bound by the clamp plate 51, the pins 95 in the plate 50 serving to insure the accurate axial positioning of the lens in the machine relatively to the pattern.

The hand clamp 94 is then removed and the work frame swung down into operative position placing the edge of the lens in contact with the grinding wheel.

The machine is now started, the grinding wheel rotated rapidly while the lens is rotated very slowly and as the grinder removes the surplus from the edge of the lens, the edge of the pattern 44 is forced downwardly by the spring 66 into contact with the roll 45 and the continued rotation of the pattern and the lens causes the lens to be ground to the exact shape controlled by the pattern.

My improved lens edge grinding machine is simple and practical in construction and effective in its operation and by its use the edges of the lens may be ground first to size in outline and then to the angles of its V-shape bevel without being obliged to remove the lens from its holder, whereby one setting of the lens in its holder is sufficient for the performing of all three of the distinct grinding operations, or the lens may be beveled from the roughed out cutting and ground to size without first grinding it at substantially right angles to its face surface.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a lens grinding machine having a grinding wheel, a frame, means tiltably

- mounted in the frame for operatively supporting a lens, and means for preventing the tiltably mounted means from being adjusted to different tilted positions while the lens is in operative proximity to the grinding wheel.
2. An attachment for lens grinding machines in combination with a grinding wheel, consisting of a cradle supporting frame, a 10 tiltably mounted cradle in the frame, means in the cradle for operatively supporting a lens, and means for preventing the cradle from being adjusted to different tilted positions without removing it from its operating 15 proximity to the grinding wheel.
3. In a lens grinding machine, a forked cradle supporting frame, a cradle pivotally mounted in said frame carrying means for supporting the lens, a notched disk fixed to 20 move with said cradle and a latch bolt normally in engagement with one of said notches to lock the cradle in different pivotally-adjusted positions, and means for preventing the unlocking action of the bolt until 25 said frame has been raised a predetermined distance.
4. An attachment for lens grinding machines in combination with a grinding wheel consisting of means for supporting the lens 30 in proximity to the wheel, means for rotating the support with its lens, means whereby said supporting means may be shifted to present the edge portion of the lens at different angles to said wheel, and means 35 whereby the lens support must be shifted to remove the lens from contact with the wheel during the shifting operation.
5. In an attachment for lens grinding machines, a frame, a cradle pivotally mounted 40 in said frame, means for operatively mounting a lens in said cradle, and adjustable means to move said cradle with relation to said frame transversely of the pivot of said cradle to center the lens with respect to its 45 thickness on the axial line through the cradle pivots.
6. In a lens grinding machine, a frame, a cradle pivotally mounted in said frame, means in said cradle for operatively mounting a lens, yieldable means to move said cradle in one direction, and threaded means to move said cradle in the opposite direction with relation to the frame transversely of the pivot of said cradle, whereby the lens may be 50 centered with respect to its thickness on the 55 pivotal axis of said cradle.
7. An attachment for lens grinding machines in combination with a grinding wheel consisting of a frame pivotally mounted adjacent the wheel, a head member longitudinally 60 slidable in said frame, said head having work-clamping means and a pattern member mounted thereon, a roll on said frame for engaging the pattern member, means for rotating said work clamp and 65 pattern in unison, and means for adjusting said frame transversely of its pivots whereby it may be adjusted to be swung about an axis passing through substantially the center of the lens to different positions to present 70 different edge portions of the work at angles at each side of a perpendicular to the grinding surface of the wheel.
8. An attachment for lens grinding machines comprising a cradle-supporting 75 means, a cradle pivotally mounted in said means, a head having lens-mounting means reciprocably mounted in said cradle, a pattern on said head, a roll on said cradle engaging said pattern, a spring carried by 80 said cradle causing continuous contact of said roller and pattern, means for rotating said lens mounting and said pattern, means for adjusting said cradle transversely of the pivots of said cradle whereby it may be ad- 85 justed to be swung about an axis passing through substantially the center of the lens to present the work at an angle at each side of a perpendicular to the grinding surface of the wheel. 90

In testimony whereof I affix my signature.

HARRY T. DANIELS.
